Primary Examiner — Cathron C Brooks*Assistant Examiner* — Christian P. McLean(74) *Attorney, Agent, or Firm* — Nancy J. Flint, Attorney At Law, P.A.; Nancy J. Flint, Esq.(57) **CLAIM**

The ornamental design for a lighted vehicle advertising system, as shown and described.

DESCRIPTION

FIG. 1 is a perspective view of a lighted vehicle advertising system, showing the new design;

FIG. 2 is an exploded view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof; and,

FIG. 9 is a front view of the design of FIG. 3 shown in a non-claimed environment.

The broken lines illustrate the environment of the design and form no part of the claim.

1 Claim, 7 Drawing Sheets(56)
